US0D1089086S

(12) **United States Design Patent** (10) **Patent No.:** **US D1,089,086 S**
(45) **Date of Patent:** **** Aug. 19, 2025**

(54) **ELECTRICAL WIRELESS CHARGER**

(71) Applicant: **Shenzhen Mgctech Co., Ltd.**,
Guangdong (CN)

(72) Inventor: **Jiedan Li**, Hunan (CN)

(**) Term: **15 Years**

(21) Appl. No.: **29/982,671**

(22) Filed: **Jan. 7, 2025**

(30) **Foreign Application Priority Data**

Jan. 3, 2025 (CN) 202530003814.X

(57) **CLAIM**

The ornamental design for a electrical wireless charger as shown and described.

DESCRIPTION

FIG. 1 is a perspective view of a electrical wireless charger showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of an encircled portion of the electrical wireless charger labeled **9** in FIG. 1;

FIG. 10 is enlarged view of an encircled portion of the electrical wireless charger labeled **10** in FIG. 1;

FIG. 11 is an enlarged view of an encircled portion of the electrical wireless charger labeled **11** in FIG. 1; and,

FIG. 12 is an enlarged view of an encircled portion of the electrical wireless charger labeled **12** in FIG. 2.

The broken lines depict portions of the electrical wireless charger and form no part of the claimed design.

The dot dash line is included for the purpose of illustrating the bounds of the enlarged view and forms no part of the claimed design.

1 Claim, 12 Drawing Sheets
